CLAIM

The ornamental design for a mouse, as shown and described.

DESCRIPTION

FIG. 1 is a perspective view of the design;

FIG. 2 is a reduced scale top view of the design;

FIG. 3 is a bottom view of the design;

FIG. 4 is a front view of the design;

FIG. 5 is a rear view of the design;

FIG. 6 is a right side view of the design; and,

FIG. 7 is a left side view of the design.

The equidistant broken lines shown in the drawings are for
illustrative purposes only and form no part of the claimed
design.
